UNITED STATES PATENT OFFICE

2,473,213

KITE PLANE DEVICE

Martin E. Nissen, Hutchinson, Minn.

Application March 26, 1946, Serial No. 657,123

1 Claim. (Cl. 244—155)

1

This invention relates to kite apparatus and more particularly to a toy airplane device adapted to be employed with a kite.

A main object of the invention is to provide a novel and improved toy airplane device adapted to be mounted on a kite string, said airplane device being provided with a releasable parachute which is automatically dropped when the toy airplane ascends to a predetermined elevation on the kite string.

A further object of the invention is to provide an improved parachute carrier in the form of a toy airplane mounted on a kite string and adapted to be elevated by air currents to a position adjacent the kite, whereupon its parachute is dropped and the toy airplane descends along the kite string.

Further objects and advantages of the invention will become apparent from the following description and claims and from the accompanying drawings, wherein:

Figure 1 is a side elevational view of a kite and toy airplane apparatus constructed in accordance with the present invention.

Figure 2 is a detail side elevational view, partly in cross-section, of the toy airplane employed in Figure 1.

Figure 3 is a top plan view of the toy airplane shown in Figure 2.

Figure 4 is a cross-sectional view taken on line 4—4 of Figure 2.

Figure 5 is a cross-sectional detail view taken on line 5—5 of Figure 2.

Referring to the drawings, 11 designates a kite which is provided with the usual kite cord 12. Mounted on cord 12 is a toy airplane 13, said toy airplane comprising a hollow body portion 14 formed of suitable light sheet material such as light gauge aluminum, cardboard, or the like, said body portion being open at each end and shaped in the form of an airplane fuselage. Journaled inside body portion 14 adjacent the front end thereof are a pair of grooved pulleys 15 and 16 and journaled adjacent the rear end of the hollow body portion are a pair of grooved pulleys 17 and 18, the kite cord 12 being threaded through the grooved pulleys 15, 16, 17 and 18 so that the toy airplane 13 is supported on said pulleys and guided thereby for free movement in either direction along the length of kite cord 12.

Pivotedly mounted in the forward portion of fuselage 14 is a transverse shaft 19 having secured to the laterally extending end portions thereof wing elements 20, 20. The interior portion of shaft 19 has rigidly secured thereto a tab

2

member 21 extending in the same plane as wing elements 20, 20. Tab member 21 is connected by a spring 22 to the interior wall surface of fuselage 14 to thereby bias the wing elements 20, 20 to a horizontal position. The wing elements 20, 20 may be releasably locked in vertical position by a resilient detent member 23 secured at one end to the bottom wall of fuselage 14 and formed at its free end with a shoulder 24 adapted to cooperate with tab member 21 to at times maintain the wing elements 20, 20 in their vertical positions. When detent member 23 is depressed shoulder 24 moves downwardly to release tab member 21, thus allowing spring 22 to move the wing elements to their horizontal position.

Secured to detent member 23 is an arm 25 having secured thereto a rearwardly extending rod 26 which projects through the rear end of fuselage 14 and is formed with a loop 27 which encircles kite cord 12. Said kite cord is provided with a longitudinally adjustable stop member 28, which may be a cork or the like, which is mounted on the cord at a desired position adjacent kite 11. When loop 27 contacts stop member 28 as the toy airplane 13 moves rearwardly up the length of cord 12, detent member 23 is depressed, releasing the wing elements 20, 20.

Pivotedly secured to the bottom of fuselage 14 adjacent the middle portion thereof is a U-shaped parachute carrier member 29. A toy parachute 30 in folded condition is adapted to be disposed between the arms of carrier 29. Secured to the upper arm of the carrier and extending laterally of the fuselage is an arm 31 which extends vertically upwardly when the carrier is in horizontal position. Cooperating with the top end of arm 31 is a gravity-biased detent member 32 pivotedly secured to the side wall of fuselage 14 adjacent and above arm 31. Detent member 32 is formed with a shoulder 33 adapted to releasably engage the upper end portion of arm 31 and is formed with an extension 34 extending in the path of movement of a wing element 20 as said wing element moves to its horizontal position.

When the parachute 30 is loaded between the arms of carrier 29 and detent member 32 is engaged with the upper end portion of arm 31, as shown in Figure 2, the carrier is retained in a position adjacent the bottom portion of fuselage 14. When the wing elements 20, 20 are released responsive to the abutment of loop 27 with stop member 28 as the toy airplane moves to its top end position on cord 12, detent member 32 is lifted by a wing element 20 and carrier 29 is released. Said carrier swings by gravity to its free depending

position, as shown in Figure 1, and allows parachute 30 to drop out.

In operation, wing elements 20, 20 are set to their vertical positions, as shown in Figure 2. The toy airplane is moved rearwardly and upwardly along cord 12 by the action of air currents against the depending wing elements 20, 20. When loop 27 moves into abutment with stop member 28 adjacent kite 11, wing elements 20, 20 are released and move to their horizontal positions, thereby lifting the detent members 32, 32 and releasing carrier 29. Parachute 30 drops out of the carrier and the toy airplane 13 then glides down the kite cord 12, as shown in Figure 1, since the wing elements 20, 20 are now in a position to offer minimum resistance to air currents in the direction of said kite cord.

While a specific embodiment of a toy airplane and kite apparatus has been disclosed in the foregoing description, it will be understood that various modifications within the spirit of the invention may occur to those skilled in the art. Therefore, it is intended that no limitations be placed on the invention other than as defined by the scope of the appended claim.

What is claimed is:

A kite cord carried toy airplane comprising a hollow, elongated fuselage through which said cord passes, grooved pulleys journaled in said fuselage near the opposite ends thereof supporting said fuselage on said cord for minimum frictional resistance to movement of said fuselage along said cord, a shaft extending transversely of said fuselage, wing elements supported by said shaft one at each side of said fuselage for pivotal movement between a substantially vertical and a substan-

tially horizontal position, spring means in said fuselage resiliently urging said wing elements to horizontal position, latch means in said fuselage releasably holding said wing elements in substantially vertical position, trigger means operatively connected with said latch means and operated by a stop on said cord to release said wing elements for movement to their substantially horizontal positions by said spring means, a U-shaped carrier pivotally connected at its closed end to the underside of said fuselage, and latch means pivotally mounted on said fuselage and engageable with said carrier to releasably hold said carrier in substantially horizontal position, said carrier latch means being positioned for operative engagement by one of said wing elements in moving from its substantially vertical to its substantially horizontal position to release said carrier for movement by gravity from its substantially horizontal to its substantially vertical position to discharge an object therefrom.
